UNITED STATES PATENT OFFICE.

EDMUND I. CUTTER, OF NORWOOD, OHIO, ASSIGNOR TO THE AMERICAN LAUNDRY MACHINERY COMPANY, OF NORWOOD, OHIO, A CORPORATION OF OHIO.

DELINTING DRYING TUMBLER.

Application filed April 23, 1920. Serial No. 376,135.

To all whom it may concern:

Be it known that I, EDMUND I. CUTTER, a citizen of the United States, residing at Norwood, in the county of Hamilton and 5 State of Ohio, have invented certain new and useful Improvements in Delinting Drying Tumblers, of which the following is a specification.

This invention relates to the class of laundry dry machines and more especially to drying apparatus, the purpose of this invention being to remove the lint from the air after its passage through the drying chamber.

The type of device to which this invention applies, as for instance the drying tumbler, comprises in general a heating chamber, a drying chamber, and an air chamber, a fan being located within the last named chamber for forcing a current of air through 10 the heating chamber, thence through the drying chamber, wherein is contained the laundry to be dried, and thence back to the air chamber; from which point the air might be expelled from the machine casing 15 or part of it re-circulated through the machine. These several chambers have communication with each other through passages which, in the present type, are controlled by dampers operated from the outside of the machine so that air can be forced 20 through the circuit just described during the time of drying the laundry, and by proper manipulation of the dampers the heating chamber can be eliminated from this circuit 25 with the result that the fresh outside air is forced through the drying chamber and back to the air chamber for the purpose of cooling the laundry before its removal from the tumbler. This particular type of device including steam pipes 30 and baffle plates 35 will be more fully understood from the description set forth in the Patent No. 1,424,994, granted August 8, 1922, to this applicant.

It having been found that more or less lint from the laundry is picked up by the air in its passage through the drying chamber, it has been deemed desirable to remove such lint from the air before its return to 40 the fan chamber or before its return to the air of the room in which the drying chamber is located. The means devised by applicant for accomplishing this purpose is located within the air chamber and is in communication with the drying chamber. By

embodimenting this invention in the several types of drying machines, it will be possible to keep the lint out of the fan, the lint will be prevented from passing through the rest of the machine and will not be allowed to pass 60 to the atmosphere of the room in which the machine is located and where employees are engaged at work. Other advantages will be apparent to those who are familiar with the 65 art.

Different forms of structure for carrying out applicant's invention will suggest themselves to those skilled in the art, but the form preferred by applicant will be understood from the following detailed description 70 and claims when considered in connection with the accompanying drawing.

Fig. 1 is a vertical transverse section of the combination in which is embodied applicant's invention; Fig. 2 is a transverse 75 vertical section through the delinting device; and Fig. 3 is a detail view partly in section of the valve used in connection with the delinting device.

By the action of fan 4 which is covered 80 by casing 5 within the air chamber 2, fresh outside air is drawn through chamber 6 and forced through passage-way 7 when damper 8 is in the full line position as shown in Fig. 1; thence through the heating chamber 1 in which are located steam pipes 30, through passage-way 12 when damper 11 is in open position as shown in full lines in Fig. 1, to the drying tumbler 13 which has a wall of foraminous material. 90 After passing through the drying chamber the air is forced back to air chamber 2, from which chamber it is expelled from the casing through outlet 34. The tumbler 13 which is given rotary motion back and forth 95 is also provided with baffle members 31 and a door 33 through which access may be had to the laundry upon opening door 32 mounted on the main outside casing of the machine.

When damper 8 is in open full line position as indicated in Fig. 1, and as above referred to, damper 10 occupies a closed position as indicated in full line position in Fig. 1, whereby passage-way 9 between the drying tumbler 13 and air supply chamber 6 is cut off. However, when it is desired to cool 105 the laundry preparatory to its removal from the tumbler, the positions of dampers 8, 10 and 11 are changed to those indicated by 110

dotted lines in Fig. 1 so that fresh outside air is then drawn by the fan from chamber 6 through passage-way 9 to the drying tumbler, whence it is forced through passage-way 14 back to the air chamber 2 and to the outside atmosphere through outlet 34. In either case, as will be seen from the drawing, the air as a result of its passage through the drying tumbler 13, will gather more or less lint from the laundry. It is proposed by applicant to remove this lint by deflecting the lint-laden air through passage-way 15 which is formed between a curved plate member 16 secured to the wall of the main casing as at 29, and that portion of the wall indicated at 17. The air carrying the lint is then forced from passage-way 15 through the main delinting device, which consists of a trough member 19 secured to wall 17, as at 18, and extending between the side walls of the machine casing to which its ends are secured as at 36 and 37. The discharge pipes from the trough 19 extend out through openings 38 and 39 in the side wall of the machine casing, as seen in Fig. 2. The lower edge portion of plate 16 extends slightly within trough 19 and is deflected toward the drying chamber, as shown in Fig. 1, thereby forcing the air to be again deflected from the near side of the trough and in this way cause the air to pass over practically the entire surface area of the fluid body. The comparatively restricted passage between plate 16 and wall 17 will give sufficient force to the air to cause the lint to be deposited upon the surface of the fluid body.

This trough member 19 contains a fluid to a point just below the lower edge of plate member 16 so as to leave a passage-way for the air from the lower end of the passage 15 to the air chamber 2 without forcing the air through the water in trough 19. Any suitable fluid may be used, water having proved very satisfactory. According to applicant's invention the lint will be deposited in the fluid contained in trough 19 and the air allowed to pass into air chamber 2 free of such lint, which action corresponds somewhat to that of a filter. Since most of this lint will remain upon the surface of the fluid in trough 19 it will be drawn off through over-flow pipe 23, as better indicated in Fig. 2, and thence out through discharge 25 when the valve 24, shown in Fig. 3, is in the position there indicated, a continuous supply of fluid being received through inlet pipe 20 so that there will normally be a constant flow through the trough. That portion of the lint which sinks to the bottom of trough 19 may be removed through pipe 22 when valve 24 is in position to allow communication of the pipe 22 with discharge pipe 25, which valve position may be obtained by turning handle 26 so as to

bring its lower end against stop 28. By turning handle 26 so as to come against stop 27 the valve 24 may be positioned as indicated in Fig. 3. With a constant fluid supply through inlet 20 it will be clear that the lint will be readily removed from the bottom of the trough 19 upon proper setting of the valve 24. It will be apparent that the level of the fluid in trough 19 can be regulated by adjustment of valve 24.

What I claim is:

1. A drying tumbler, comprising a casing including an air chamber, a heating chamber, and a drying chamber, means for causing the flow of air through said chambers, and means for automatically and successively presenting unpolluted portions of liquid for exposure to the flowing air for collecting foreign matter therefrom.

2. A drying tumbler, comprising a casing including an air chamber, a heating chamber, and a drying chamber, means for causing the flow of air through said chambers, a receptacle containing liquid exposed to the air current, and means for automatically withdrawing contaminated liquid from said receptacle and supplying unpolluted liquid thereto for removing foreign matter from said air current.

3. A drying tumbler, comprising a casing including an air chamber, a heating chamber, and a drying chamber, means for causing the flow of air through said chambers, and means for causing the flow of liquid in said casing in a direction substantially transversely to the direction of the air current for removing foreign matter therefrom.

4. A drying tumbler, comprising a casing including an air chamber, a heating chamber, and a drying chamber, means for causing the flow of air through said chambers, a body of liquid exposed to the air current, and means for withdrawing contaminated liquid therefrom and supplying unpolluted liquid thereto for removing foreign matter from the air current.

5. In a drying machine, the combination of an air chamber, a heating chamber, a drying chamber, means for forcing air through the said several chambers, a body of fluid for removing the lint from the air after its passage through the drying chamber, and means for deflecting the air in its passage through the machine, said last named means comprising a curved plate member arranged so that the air from the drying chamber will be deflected by the concave surface of said plate member and impinge upon the surface of the fluid.

6. In a drying machine, the combination of an air chamber, a heating chamber, a drying chamber, means for forcing air through the said several chambers, a body of fluid for removing lint from the air after

- its passage through the drying chamber, and a concave plate member for deflecting the air in its passage through the machine associated with the wall of the drying chamber to form a passage-way between the drying chamber and said plate member, whereby the lint-laden air will be deflected by the concave face of said plate member and be caused to impinge upon the fluid body.
7. In a drying machine, the combination of an air chamber, a heating chamber, a drying chamber, means for forcing air through the said several chambers, a body of fluid for removing lint from the air after its passage through the drying chamber, and a concave plate member for deflecting the air in its passage through the machine associated with the wall of the drying chamber to form a passage-way between the drying chamber and said plate member, the lower edge of said plate member terminating within said trough member at a point above the level of the fluid, whereby the lint-laden air will be deflected by the concave face of said plate member and be caused to impinge upon the fluid body.
8. In a drying machine, the combination of an air chamber, a heating chamber, a drying chamber, means for forcing air through the said several chambers, means comprising a circulating fluid for removing lint from the air after its passage through the drying chamber, and means for deflecting the air in its passage through the machine, said last named means comprising a curved plate member terminating at its lower edge at a point above the high level of said fluid body and substantially midway between the sides of said trough, said plate member having an increased curvature across the path of the air as it enters said trough, whereby the air from the drying chamber will be deflected by the concave surface of said plate member and be caused to traverse practically the entire surface 45 area of said fluid body.
9. In a drying machine, a delinting device comprising a trough member for containing fluid, said trough member being provided with means for attachment within a 50 drying machine casing and having a fluid inlet at one end, an overflow outlet at its other end and a drain outlet in the last named end portion, said outlets having a common discharge with a 2-way valve for 55 controlling the passage-ways through the outlets and the said common discharge and a curved deflector plate with means for attaching said plate within the casing of a drying chamber, said plate being designed 60 to deflect the lint-laden air into the said trough member.
10. In a drying machine, a delinting device comprising a trough member for containing fluid, said trough member being provided with means for attachment within a 65 drying machine casing and having a fluid inlet at one end, an overflow outlet at its other end and a drain outlet in the last named end portion, said outlet having a 70 common discharge with a 2-way valve for controlling the passage-ways through the outlets and the said common discharge.
11. A drying tumbler, comprising a casing having an air chamber, a heating chamber, and a drying chamber, means for causing the flow of air through said several chambers, and a container for liquid mounted upon the walls of said casing in the path of the air after its discharge through the drying chamber, said container being provided at one end with means for continuously supplying liquid thereto and at the other end with an open discharge for said liquid.
- In testimony whereof I affix my signature.

EDMUND I. CUTTER.
